UNITED STATES PATENT OFFICE.

JERRY L. STAIR, OF CHICAGO, ILLINOIS.

COVE REFLECTOR.

Application filed June 2, 1922. Serial No. 565,402.

To all whom it may concern:

Be it known that I, JERRY L. STAIR, a citizen of the United States, residing at Chicago, in the county of Cook and State of Illinois, have invented certain new and useful Improvements in Cove Reflectors, of which the following is a specification.

The present invention is related to reflectors for lighting fixtures for indirect illumination, and is more particularly concerned with such fixtures adapted for the diffusion of light from concealed sources.

More specifically stated, the invention has to do with cove reflectors or those located in recesses, niches, or the like formed in walls, and especially in cornices thereof, by which the light is projected in a highly diffused manner within the room or similar enclosure without visibility of the illuminating units, and the resultant glare incident to such visibility. The advantages flowing from indirect illumination generally are recognized, particularly in auditoriums, theaters, and similar places for public gatherings, and the value of such illumination is indicated by the numerous installations of this character which are constantly being effected. The invention aims to promote and extend these installations.

The invention likewise has in view the production of a novel form of cove reflector which is so constructed as to break up effectively the light rays emanating from the lighting units, whereby the surface illuminated will be wholly free from streaks or images and a more even diffusion of the light attained.

Furthermore, the invention seeks to provide a reflector such as referred to which is of a unitary character, thereby enabling ready aligning and assembly of a plurality of the same in any required number to provide for varying lengths of continuous reflecting surfaces. The invention, therefore, adapts itself to easy and convenient installation in varying lengths of recesses.

Other objects and advantages will appear as the nature of the improvements is better understood, the invention consisting substantially in the novel construction, combination and arrangement of parts herein-after fully described, illustrated in the ac-

companying drawings, and finally pointed out in the appended claims.

Fig. 1 is a front elevation of a cove reflector embodying the herein-described invention; 55

Fig. 2 is a top plan view thereof;

Fig. 3 is a cross-sectional view, as on the line 3—3, Fig. 2. 60

Referring now in detail to the accompanying drawings, the numeral 10 designates the body of the herein-described reflector. Preferably this is formed of glass the exterior of which is silvered to impart the required reflecting qualities thereto, and this reflecting backing, in turn, is covered with a layer of opaque material so that the resultant reflector is of the silver mirrored type. The latter is known in the art. 65

It has been stated that the invention contemplates a reflector of a unitary character; that is to say, the invention aims to provide a reflector which is of such construction that it may be placed end to end with other similar reflectors, and when these units are thus aligned a substantially continuous reflector is produced which may be of varying lengths to accommodate the length of the particular cove or recess wherein the reflector is to be positioned. At the same time, it is desirable that the particular unit shall be of such size and formation that it will possess the necessary capacity for use as an individual reflector, thus adapting the individual unit to the needs to which a reflector of this nature may be subjected. To this end, the body 10 is of substantially elongated form, the ends thereof being cut square, as at 11, so that when brought into abutting relation with a contiguous reflector or unit the adjacent ends will fit against each other and permit proper aligning of the units. 90

At a point substantially midway between the ends of the reflector the body 10 is provided with a ridge 12, this ridge dividing the end portions of the body into sections 13 and 14 of generally similar contour, and at a point in said ridge 12 an opening 15 is located for receiving a suitable fastening device for holding the reflector in position of use. By reason of the ridge 12, which is substantially in the plane of ends 11, the sections of the body 10 at either side of the 95

100

ridge are generally concave at their interior faces, and each of said sections has formed therein an enlarged opening 16, said opening being designed to receive an illuminating element such as an electric lamp.

The lower edge of each of the openings 16 has a depending flange 17 formed thereat, said flange being adapted to set within a socket for sustaining the body of the reflector in its position of use.

To provide for the effectual diffusion of the light emanating from the illuminating units fitted in the openings 16 is also one of the objects of the present invention. As illustrated in Fig. 3, it will be observed that the body 10 has a trough-like configuration, the back 18 being curved upwardly and rearwardly and substantially vertical, except as modified by the concave form of its 20 interior, while the bottom 19 is curved upwardly and forwardly, the free edges of the back 18 and bottom 19 defining an opening through which the diffused light passes to the space to be illuminated.

In order that the light rays may be broken up in the most effective manner, and thus attain the highest degree of diffusion of the light, the bottom 19 of each of the sections 13 and 14 has formed therein substantially 30 parallel corrugations 20, which corrugations radiate from the opening 16 of that section. These corrugations 20, therefore, extend forwardly and upwardly.

The back 18 of each of the sections 13 and 35 14 likewise is provided with a plurality of substantially parallel corrugations 21, and these corrugations of each of said sections also radiate from the opening 16 of that section, but the corrugations 21 extend rearwardly and upwardly. There is thus provided in each section two independent groups of corrugations, one of which extends forwardly from the opening 16, and the other rearwardly therefrom. While the 40 corrugations 20 and 21 radiate from the opening 16, the corrugations of each of these groups are substantially straight, considered from the standpoint of the transverse dimension of the body 10 of the reflector.

In order that the light rays may be broken up to a further extent, the corrugations 20 are intersected by spiral corrugations 22, and the corrugations 21 are also intersected by similar spiral corrugations 23.

By reason of the corrugations 20 and 21, and the intersecting spiral corrugations 22 and 23, the interior of the reflector is of such construction that an even diffusion of the light follows, and the surface illuminated by the light reflected thereby is free from streaks and images which would result were the interior surface of the reflector plain.

In the use of the herein-described invention, one or more of the reflectors is or are

placed in a cove in a cornice or other point of concealment of the walls of the space to be illuminated. The lighting units, therefore, are concealed, and the illumination of the space is effected indirectly rather than directly, as would be the case were the units visible. The rays of light emanating from the lamps positioned in the opening 16 impinge against the back 18 and the bottom 19, but these incident rays are effectually broken up because of the corrugated surfaces with which they contact, so that the light projected from the reflector is highly diffused, and the surfaces of the ceiling or wall in proximity to the reflector are freed entirely from images or streaks. Thus, the entire room in which the reflectors are placed becomes illuminated with a soft indirect light, and there is no glare to offend the eye of the observer, due to the effectual diffusion of the light from the illuminating units.

The invention is primarily intended for use with the construction of holder set forth in the application of Paul M. Hotchkiss, filed August 29, 1921, Ser. No. 496,214, but may be employed in other relations where concealed lighting units are utilized, and where a highly diffused light is desired.

I claim:

1. A reflector of the class described, comprising a trough-like body having an opening formed therein for receiving a lighting element and including an upwardly extending curved reflecting back and a forwardly extending curved reflecting bottom, the free edges of said back and said bottom defining an opening through which the light is projected, the free edge of the bottom being in a lower plane than the free edge of the back, whereby the light is projected forwardly by the back and upwardly by the bottom.

2. A reflector of the class described, comprising a trough-like body having an opening formed therein for receiving a lighting element, said body including an upwardly extending reflecting back and a forwardly and upwardly extending bottom, the free edges of said back and bottom defining an opening through which the light is projected, both the back and the bottom being each provided with independent groups of corrugations radiating from said opening in opposite directions, each of said groups of corrugations being intersected by other groups of spiral corrugations, thereby breaking up light rays emanating from the lighting element and for diffusing the light projecting from the reflector.

3. A reflector of the class described, comprising a trough-like body having a ridge at a point intermediate its ends, whereby to divide said body into a plurality of sections, the interior of each of said sections being

substantially concave, said body being provided also with a plurality of openings, one of which is arranged at each side of said ridge, said body also including an upwardly 5 extending reflecting back and a forwardly and upwardly extending reflecting bottom, the free edges of said back and bottom defining an opening through which the light is projected, both the back and the bottom 10 being each provided with an independent group of corrugations radiating from each of the openings for receiving the lighting elements, and other groups of spiral corrugations intersecting the first mentioned corrugations, whereby to break up the light 15 rays from the lighting elements and diffuse the light projected by the reflector.

4. A reflector of the class described, comprising a trough-like body having an opening formed therein for receiving a lighting element and including an upwardly and rearwardly extending curved reflecting back and a forwardly extending curved reflecting bottom, the free edges of said back and said 20 bottom defining an opening through which the light is projected, the back having a group of corrugations radiating upwardly and rearwardly from said opening, and the bottom also having a group of corrugations 25 radiating forwardly from said opening and

in opposite direction to that of the corrugations of the back, whereby to break up the light rays emanating from the lighting element and to diffuse the light projected from the reflector.

5. A reflector of the class described, comprising a trough-like body having an opening formed therein for receiving a lighting element and including an upwardly and rearwardly extending curved reflecting back and a forwardly extending curved reflecting bottom, the free edges of said back and said bottom defining an opening through which the light is projected, the back having a group of corrugations radiating upwardly and rearwardly from said opening, and the bottom also having a group of corrugations 40 radiating forwardly from said opening and in opposite direction to that of the corrugations of the back, both the back and the bottom also being each provided with a group of spiral corrugations intersecting the first mentioned corrugations, whereby to break up the light rays emanating from the lighting element and to diffuse the light 45 projected from the reflector.

In testimony whereof I have hereunto subscribed my name.

JERRY L. STAIR.
